UNITED STATES PATENT OFFICE.

ANDREW OBITZ, OF PITTSBURG, PENNSYLVANIA.

VEHICLE ATTACHMENT.

SPECIFICATION forming part of Letters Patent No. 769,564, dated September 6, 1904.

Application filed November 7, 1903. Serial No. 180,198. (No model.)

To all whom it may concern:

Be it known that I, ANDREW OBITZ, a citizen of the United States of America, residing at Pittsburgh, in the county of Allegheny and State of Pennsylvania, have invented certain new and useful Improvements in Vehicle Attachments, of which the following is a specification, reference being had therein to the accompanying drawings.

This invention relates to certain new and useful improvements in vehicle attachments; and it relates specifically to a device adapted to be attached to a wagon for assisting the rear wheels thereof to turn out of engagement with the rails of a car-track.

In the turning of a wagon from off the car-tracks it is a comparatively easy matter to cause the front wheels to leave the rails by reason of the angle to which the wheels are moved with respect to the rail by turning the team from off the track; but this is not true of the rear wheels of the wagon, which have a tendency to slide on the rails until such time as the angle of the vehicle with respect to the rails is such as to prevent further sliding of the rear wheels and cause them to ride up over the rail-tread.

It is the object of my invention to provide novel and effective means for engagement underneath the rear wheels of the vehicle to cause said wheels to pass readily up over the rail-tread without sliding on the edge thereof, as is ordinarily the case.

Briefly described, the invention comprises a shoe carried on an arm suspended from the rear axle, one of these shoes being provided for each rear wheel. Means is provided for holding the shoe and arm normally suspended in the inoperative position, and means is provided whereby when the shoe is dropped into the operative position and the wheel passes over the same the said shoe will be carried around by the wheel during the revolution of the latter and be deposited on its supporting means ready for the next operation.

The construction involved will be herein-after more specifically described in detail and then particularly claimed, and in describing the invention in detail reference is had to the accompanying drawings, forming a part of

this application, and wherein like numerals of reference indicate like parts throughout the several views, in which—

Figure 1 is a top plan view of a wagon-frame having my improved device attached thereto. 55 Fig. 2 is a side elevation of a part of a wagon equipped with my device. Fig. 3 is a detached detail perspective view of the form of brake-lever and suspension-plate. Fig. 4 is a detached detail perspective view of one of the 60 carrying-pins connected to the spokes of the wheel. Fig. 5 is a plan view of a part of the axle, showing the cam-disk in horizontal section. Fig. 6 is a detached detail perspective view of the arm and shoe, both partly broken 65 away. Fig. 7 is a front elevation of one of the cam-disks with the arm in cross-section.

To put my invention into practice, I provide on the rear axle 1 just back of the spindles 2 a cam-disk 3, which is mounted on the axle 1 and firmly secured in any desirable manner, as by angle-brackets 4, as shown. Rotatable on the spindles 2 or on the rounded portion of the axle just back of the spindle, as may be desired, is a ring 5, the ends 6 of which 70 receive between them the one end of the arm 7, fastened by means of a bolt 8 and nut. This arm 7 carries at its lower end a shoe 9, which may be suitably secured thereto or may be an integral part of the arm, as may be desired, 80 and is preferably corrugated or notched, as shown at 10, in order to be more receptive to readily remain on the rail in position to receive the tire of the wheel. The arm carries a guide 11, which extends back of the cam-disk 3, the latter being received between the guide-arm 11 and the arm 7. Where the vehicle upon which the device is is of a form employing a brake-beam 12, the shoe 9 and arm 7 will be supported by the brake-beam, as seen 85 in Fig. 1, the brake-beam being preferably pivoted at its center in order that either half thereof may be moved whereby to drop either one of the devices, as may be desired, onto the rail. Where no brake-beam is employed on 90 the vehicle, the brake-lever 14, which carries the brake-shoe 15, may have on its angular portion a supporting-plate 16, upon which the shoe 9 is adapted to rest. When the lever 14 or brake-beam is moved forward so as to re- 95 100

move the support for the arm, and thus allow the shoe to fall into engagement with the rail in front of the wheel, as seen in Fig. 2, the wheel will ride up on the shoe and be elevated, whereby to permit its ready turning off of the rail upon which it was traveling. In order to bring the device again into its normal position and ready for another operation, I provide on the spokes of the wheels carrying pins 17, which I preferably attach to the spokes by the construction herein shown, that of providing the clips 18 to embrace the spoke 19 and secured to the spoke by means of a bolt or rivet passing through the clip and through the spoke. In the present illustration I have shown one of these pins attached to each spoke of the wheel, and this construction is preferable, for the reason that the arm may be picked up by the pin immediately upon said shoe passing out of engagement with the wheel without necessitating the turning of the wheel until such time as the pin would come in engagement with the arm in event only one pin was used. The purpose of the cam-disk 3 is to move the arm 7 laterally as it comes to its rest or normal position, so as to permit of the carrying-pin 17 passing the arm without striking the same when the said arm is in its raised position.

I generally make the opening in the disk 3 of considerable diameter and provide the disk with slots 3', through which the bolts 4', that secure the disk to brackets 4, are passed, and also slot the brackets. This construction permits of securing the disk to different-sized axles without necessitating a different disk for each size of axle.

As either of the arms 7 are dropped they are moved toward the wheel by the outwardly bent portion of the disk 3, so as to lie in the path of the pins. Thus after the shoe 9 has cleared the wheel, or, in other words, the wheel has passed over the same, the arm will be carried upwardly until the unbent or flared

portion 3^a of the disk is encountered, at which point, the arm having passed over its pivotal point, it is moved out of engagement with the pins, and thus allowed to drop by gravity to the position indicated in Fig. 1.

It will be obvious that various changes may be made in the details of construction without departing from the general spirit of my invention.

Having fully described my invention, what I claim as new, and desire to secure by Letters Patent, is—

1. In a device of the character described, the combination with the rear axle, of a ring rotatably mounted thereon, an arm carried by said ring, a shoe at the outer end of said arm, a guide-arm carried by the first-mentioned arm, a cam-disk on the axle to be received between the arm and the guide-arm for moving said arm laterally, means carried on the wheel-spokes for engagement with the arm after the shoe has cleared the wheel, and means for supporting the arm and shoe normally in the inoperative position, substantially as described.

2. In a device of the character described, an arm rotatably mounted on the rear axle, a shoe carried by said arm at its outer end, a guide-arm carried by the first-mentioned arm, a cam-disk received between the arm and guide-arm, a cam mounted on the axle and received between the arm and guide-arm, carrying means secured on the spokes and adapted to pick up the arm after the shoe has passed out of engagement with the wheel, and means for normally supporting the arm and shoe in the inoperative position, substantially as described.

In testimony whereof I affix my signature in the presence of two witnesses.

ANDREW OBITZ.
